HANDGRIP FOR GOLF CLUBS AND THE LIKE

John M. Oldham, Detroit, Mich., assignor to
Leonard A. Young, Detroit, Mich.

Application December 31, 1931, Serial No. 584,171

1 Claim. (Cl. 273—81)

My invention relates to improvements in implement handles and more particularly to the handles or hand-grip portions of golf clubs.

It has been the practice heretofore to construct 5 golf club grip or handle portions by first spirally winding a strip or strips of cork about the club shaft and subsequently interposing a strip of leather between the convolutions of the spirally wound cork strips. This practice is objectionable 10 in that the finished handle is not uniform in contour and indentations and projections are produced upon the surface of the handle, particularly where the strips of cork join. Moreover extreme care is required in winding the cork so 15 that the convolutions will be in true spaced relation.

With these objections in mind, it is the principal object of the present invention to provide a pre-formed sleeve, formed in the making thereof, with a spiral groove in its outer surface, so 20 that a flat tape-like strip may be laid within this groove after the sleeve-like member has been applied to the golf stick shaft, whereby the surfaces of the sleeve and leather strip will lie flush 25 with each other and produce a grip which is free from indentations or projections.

A further object of the present invention is 30 to provide a hand grip for sporting implements, such as golf clubs, which includes a pre-formed tubular member of yieldable material, such as cork, and is such that it may be readily applied to any golf club shaft and when in position 35 thereon, will be firmly held against displacement.

With the above and other objects and advantages 40 in view, the invention consists in the construction, arrangement and combination of elements, all as hereinafter set forth and more particularly pointed out in the appended claim, reference being had to the accompanying drawing 45 wherein;

Fig. 1 is a side elevation of a golf club illustrative 50 of an embodiment of the present invention;

Fig. 2 is an enlarged detailed view showing the hand grip portion of the club, partly in section and partly in elevation;

Fig. 3 is a view, in elevation, of a leather strip 55 adapted to form a part of said hand grip of the club; and

Fig. 4 is a transverse section substantially upon the line 4—4 of Fig. 2.

Referring to the invention in detail, a pre-formed sleeve member 5 of suitable length and thickness, having a tapered lower end 6, is provided. This sleeve may be formed from a sheet 55 of cork or other suitable material possessing the

desired yieldable quality, or it may, if found desirable, be formed in a mold to the desired shape, size and form.

For cooperation with this cork sleeve in providing a frictional hand gripping surface, a flat 5 tape-like strip 10 of leather or other suitable material, is provided, and this strip is wound within a spiral groove 11 formed in the periphery of the sleeve and extending from end to end of the same. As shown in Fig. 2, this strip is of a width 10 and thickness to exactly fill said spiral groove with the outer surface of said strip lying flush with the periphery of the sleeve, and therefore the grip surface will be uniform throughout the length of the sleeve as the strip lies flat upon 15 the smooth, flat, continuous bottom of the groove and all indentations or projections at the surface of the grip will be eliminated.

Before winding the strip 10 into the groove 11, the walls of the groove and the contacting 20 side and edges of the strip may be coated with a suitable adhesive, so that the strip will be firmly anchored within the groove, and during this winding of the strip, it is drawn relatively taut so as to compress the wall of the bore of 25 the sleeve and press it against the shaft 1, thereby aiding in the securing of the sleeve in place upon the shaft. If found desirable, the end portion of the shaft to which the sleeve is to be applied may also be coated with a suitable adhesive to aid in securing the sleeve in place.

In order to provide a finish for the outer end 30 of the sleeve and protect the same against wear, a suitable cap 12 is attached to the end of the shaft by a removable fastening 13, and as shown, 35 an annular flange or skirt 14 may be provided on the cap to surround and overlie the outer end of the sleeve.

By the provision of a hand grip such as herein disclosed the usual gripping qualities of leather 40 and cork are had, and at the same time, a hand grip having a uniform hand grip surface is provided due to the manner in which the cork sleeve is formed and the accuracy and smoothness with which said strip may be laid within the groove 45 in said sleeve. It will also be apparent that my invention is an aid in the manufacture of golf clubs, in that the pre-formed sleeve may be readily slipped onto the handle end of the shaft and does not require the skill which is necessary in 50 winding a cork strip and uniformly spacing its convolutions, as with known constructions.

What I claim is:—

A hand grip for golf club shafts comprising a 55 continuous one piece sleeve formed of cork or

other material of limited compressible, disintegrable, and non-slip characteristics in the hand of the player and telescoped over an end portion of the shaft, said sleeve being pre-formed with a spiral groove of extended width in the exterior surface thereof; and a flat strip of a width to fit closely within said groove and of inelastic material having a smooth wear resisting exterior surface, wound about said sleeve within said groove under tension to firmly clamp and hold said sleeve in firm contact with said club shaft and protect the exposed portions of said sleeve between the turns of said groove, said strip

being of a thickness to fill said groove flush with the exterior surface of said sleeve between the turns of said strip and being cemented within said groove to firmly hold said strip throughout its entire length flat upon the bottom of said groove, said turns of said strip together providing a smooth wear resisting surface forming an extended portion of the hand grip surface with the non-slip surface of the sleeve exposed and slightly bulged between said turns by the compression of said sleeve by said strip. 5 10

JOHN M. OLDHAM.
